[57] **CLAIM**

The ornamental design for a boxing top actuator, as shown and described.

DESCRIPTION

FIG. 1 is a right side elevational view of a boxing top actuator showing my new design, the left side elevational view being a mirror image thereof;

FIG. 2 is a top plan view;

FIG. 3 is a bottom view;

FIG. 4 is a front elevation view; and

FIG. 5 is a rear elevational view thereof.
